Primary Examiner — Deanna L Pratt

(74) Attorney, Agent, or Firm — Avyno Law P.C.

(57) **CLAIM**

I claim the ornamental design for a vanity mirror, as shown and described.

DESCRIPTION

FIG. 1 is a top front perspective view of a vanity mirror. FIG. 2 is a bottom front perspective view of the vanity mirror of FIG. 1. FIG. 3 is a front view of the vanity mirror of FIG. 1. FIG. 4 is a rear view of the vanity mirror of FIG. 1. FIG. 5 is a side view of the left side of the vanity mirror of FIG. 1. FIG. 6 is a side view of the right side of the vanity mirror of FIG. 1. FIG. 7 is a top view of the vanity mirror of FIG. 1; and, FIG. 8 is a bottom view of the vanity mirror of FIG. 1. The broken lines illustrate portions of the vanity mirror that form no part of the claimed design.
